OIL BURNER

Filed April 1, 1936

UNITED STATES PATENT OFFICE

2,124,169

OIL BURNER

James S. Sheafe, Casa Grande, Ariz., assignor to
 Sheafe Engineering Company, Inc., Chicago,
 Ill., a corporation of Illinois

Application April 1, 1936, Serial No. 72,063

3 Claims. (Cl. 158—56)

My invention relates to an oil burner, and has for its principal objects, to generally improve upon and simplify the construction of the existing forms of oil burners, and particularly, those burners utilized for household heating purposes and also in smudge pots, further, to provide an oil burner that is relatively simple in construction, composed of few parts, all of which are readily accessible for the purpose of inspection, replacements and the cleaning of the interior of the burner, and further, to provide an oil burner that develops very little, if any, smoke and soot while in operation.

Further objects of my invention are, to provide an oil burner of the character referred to, with improved means for supplying air to support combustion of the liquid hydrocarbon utilized as fuel in the burner, and also to provide means for continuously delivering water to the burner, which water is converted into vapor that mixes with the air and vaporized liquid hydrocarbon, to bring about perfect combustion and consequent high efficiency of the burner in the development of heat.

With the foregoing and other objects in view my invention consists in certain novel features of construction and arrangements of parts that will be hereinafter more fully described and claimed and illustrated in the accompanying drawing in which:

The figure is a vertical section taken through the center of an oil burner constructed in accordance with my invention.

Referring by numerals to the accompanying drawing which illustrates a preferred embodiment of the invention, 1 designates a bowl that may be formed of cast or pressed metal, and formed through the upright wall of said bowl are breather apertures 1a through which air may freely circulate. Removably positioned on top of the bowl is a ring-shaped baffle plate 2 which is for the purpose of directing heated air that rises along the inner surface of the bowl toward the center thereof, thus to a certain extent concentrating the heat that is developed by the burner.

Communicating with the bottom of the chamber within the bowl 1, is an air supply pipe 8, and to control or throttle the flow of air through this pipe, the same is equipped with suitable valvular means, for instance, a manually operable damper such as 9.

Formed in the upper surface of the bottom of the bowl 1, and surrounding the upper end of the air inlet pipe 8 is a shallow channel 4 adapted

to receive water, and suitably connected to the lower portion of the bowl and communicating with channel 4 is a pipe 5 that leads from a suitable source of water supply. If desired, this water supply pipe may be taken into the bowl 5 through the side thereof.

When the burner is installed for use, it is positioned just above the bottom 7 of a stove, furnace, smudge pot or the like, and the air supply pipe 8 and water supply pipe 5 extend 10 through said bottom.

Formed on the upper surface of the bottom of the bowl 1 between the channel 4 and the open upper end of the air supply pipe 8, is a vertically disposed shoulder 10, and the surface of said shoulder and the adjacent surface of the bottom 15 of the bowl are made smooth by machining, or otherwise.

The burner proper which is positioned within the bowl just above the open upper end of air inlet pipe 8, comprises a shallow bowl 3, and formed integral with the under side of said bowl and depending therefrom is a wall 11, the lower end of which rests directly on top of the bottom of bowl 1, and against the shoulder 10. All 20 surfaces of the bowl 3 and the wall 11 are preferably machined, in order to provide smooth surfaces that may be easily cleaned and which counter-act tendency of dust, soot and the like, to adhere to said surfaces, and as the surfaces 25 of the lower end of the wall 11 are machined, a very snug joint is produced between the lower portion of wall 11, the shoulder 10 and that portion of the upper surface of the bottom of the bowl on which the wall 11 rests.

Formed through the wall 11 is a plurality of apertures 12, which permits air from the upper end of supply pipe 8 to discharge into bowl 1 directly around the body of the burner 3.

Formed through the lower portion of the upper right wall of the burner bowl 3 is a plurality of small apertures 13, which permits the hydrocarbon in either liquid or vaporized condition to discharge from the lower portion of the burner bowl.

Formed in the center of the bottom of the burner bowl 3 is an opening 14, and surrounding same is an upwardly projecting wall 15. Formed through the lower portion of this wall 15 is a plurality of apertures 16, which permits hydrocarbon in either liquid or vaporous condition to discharge from the burner bowl. A liquid hydrocarbon supply pipe 6 is connected to the burner bowl 3, and removably positioned on top of the burner bowl and resting on top of the wall 15 55

that surrounds the central opening 14, is a cover plate 17.

In the operation of my improved oil burner, a small amount of liquid hydro-carbon is permitted to flow into the burner bowl 3 through supply pipe 6, and as this liquid hydro-carbon discharges from the apertures 13 and 16 it is ignited, and the resultant heat quickly heats the burner to such a degree as to vaporize the liquid hydro-carbon as it continues to flow into the burner.

The vaporized liquid hydro-carbon discharges through the apertures 13 and 16 and burns within the bowl 1, and the air to support combustion passes upwardly through supply pipe 8 and thence through openings 12 in wall 11 to mix and burn with the liquid hydro-carbon vapor.

The flow of air to the burner may be accurately regulated by proper manipulation of the 20 valvular means or damper within pipe 3, and the flow of liquid hydro-carbon to the burner may be controlled by suitable valvular means (not shown) that is associated with supply pipe 6.

25 While the burner is in operation, a certain amount of water is permitted to flow from supply pipe 5 into channel 4, and the heat from the burner converts this water into steam which unites with the air and liquid hydro-carbon vapor in producing a highly inflammable mixture, the 30 burning of which produces a relatively high degree of heat. The addition of air and steam to the vaporized liquid hydro-carbon, insures perfect combustion of the latter, and the moisture or steam content added to the mixture is highly effective in counter-acting the development of 35 smoke and soot during operation of the burner.

An important feature of my invention is the air supply pipe 8 that supplies air to the burner within the bowl, for by extending this air supply pipe 8 downwardly a substantial distance, for instance, down to within an inch or two of the floor on which the heating appliance rests, said appliance functions as a circulation heater, that is, the air that is heated by the heater is caused to circulate through the room in which the heater is located. During such circulation the heated air rises from the heater and the cooler air is taken from a point adjacent the floor and delivered into the bowl.

50 Thus it will be seen that I have provided an oil burner that is relatively simple in construction, inexpensive of manufacture and very effective in performing the functions for which it is intended.

55 The burner comprises relatively few parts that are easily assembled or taken apart, and the construction of the burner proper and the bowl in which said burner is positioned is such, that said burner and bowl may be very easily and 60 quickly cleaned and maintained in condition to function to the greatest advantage.

While my improved burner is particularly designed for use in household heaters, stoves and furnaces, and also for use in smudge pots, the burner may be advantageously and economically employed wherever heat that is devoid of smoke and soot is required.

It will be understood that minor changes in the size, form, and construction of the various parts of my improved oil burner may be made and substituted for those herein shown and described without departing from the spirit of the invention, the scope of which is set forth in the appended claims. 5

I claim as my invention:

1. In an oil burner, an open topped bowl provided in its lower portion with an air inlet opening, a burner removably positioned within the bowl and disposed above said air inlet opening, said burner comprising a body having a liquid hydro-carbon receiving chamber, said chamber having outlets, means for delivering liquid hydro-carbon to said chamber there being an opening in the center of the bottom of said burner, an upstanding wall surrounding said opening, there being outlet openings formed in the lower portion of said upstanding wall, a cover plate resting on top of said upstanding wall and covering the chamber in the body of the burner, a wall depending from said burner body and surrounding the air inlet opening in the bowl and said last mentioned wall being provided with openings. 10 15 20 25

2. The combination with an open-topped bowl provided in its bottom with an air inlet opening and a shallow water receiving channel formed in the upper surface of the bottom of said bowl around the air inlet opening therein, of a burner body, an upstanding wall surrounding said opening there being openings formed through the lower portions of said upstanding wall, a plate removably positioned on top of the burner body and covering the chamber between the marginal wall and the upstanding wall that surrounds the central opening, there being an opening in the center of said cover plate, which opening is in communication with the opening that is surrounded by said upstanding wall, means for delivering hydrocarbon to the chamber in the burner body, a flange depending from the bottom of said burner body, which flange rests on the bottom of said bowl and surrounds the central opening therein, and said depending flange being provided with a series of openings. 25 30 35 40 45 50

3. In an oil burner, a burner body comprising a plate, a marginal wall projecting upwardly from said plate, said marginal wall being provided with perforations, there being an opening in the center of said plate, an upstanding wall surrounding said opening there being a plurality of openings formed through the lower portion of said upstanding wall, a cover plate resting on the upper ends of said walls for closing the chamber between said walls, there being an opening in the center of said cover plate, which opening registers with the opening in the bottom of said plate, a flange depending from said plate, and there being openings in said flange. 50 55 60
